UNITED STATES PATENT OFFICE.

WILLIAM C. LOUD, OF DETROIT, MICHIGAN.

LOOSE-LEAF BINDER.

1,001,539.

Specification of Letters Patent. Patented Aug. 22, 1911.

Application filed December 19, 1910. Serial No. 598,114.

To all whom it may concern:

Be it known that I, WILLIAM C. LOUD, a citizen of the United States of America, residing at Detroit, in the county of Wayne 5 and State of Michigan, have invented certain new and useful Improvements in Loose-Leaf Binders, of which the following is a specification, reference being had therein to the accompanying drawings.

10 This invention relates to loose-leaf binders, and more especially to that class thereof in which the leaves have marginal perforations through which the hook-members of the binders pass and permit free access to 15 and inspection of the leaves, and it has for one of its objects: the provision of simple and effective device of this character which may generally be opened only for a certain amount without disengaging the leaf-retaining fingers, and which may be opened 20 farther to insert or remove loose leaves only subsequently to the manipulation of the lock-member of the device, whereby the latter may also be locked in its closed-in condition. 25 The invention has furthermore, for its object the provision of a novel hinge the pin of which controls the amount of opening of the device.

Further objects of the invention will hereinafter appear and be defined in the claims.

The invention has been clearly illustrated in the accompanying drawings, in which similar characters denote similar parts, and in which—

30 Figure 1 represents a fractional top view of a temporary binder embodying my invention, in closed but unlocked condition; Fig. 2 is an end view thereof; Fig. 3 is a top view showing the binder opened to permit the leaves being turned over for inspection; Fig. 4 is an endwise view of the same; Fig. 5 represents a top view illustrating the binder spread open to permit leaves to be inserted or withdrawn; Fig. 6 shows an end 40 view thereof; Fig. 7 is a view corresponding to Fig. 1, but illustrates the binder locked; Fig. 8 shows in detail the locking hinge-rod of the device, and Fig. 9 illustrates one of the hinge-sections with its multi-part 45 slot.

The present device consists of only three movable parts, viz. the two finger-carrying plates, and the hinge-rod whereby they are jointed.

50 In the drawings, the numeral 10 denotes

one of the hinge-plates having one of its longitudinal edges cut-out to form rolled-over hinge-journals 11, which are interposed between similar journals 12 of a hinge plate 13, a rod 14 passing through all the journals and jointing the plates for pivotal movement. The plates 10, 13 are provided with arcuate fingers 10', 13', respectively, adapted to telescope into each other, as shown in Fig. 2, and concentric with the hinge-rod 14. 60

In the present instance the device is adapted to be locked against further opening movement in three distinct positions shown in Figs. 1 and 7, and 3 and 5, respectively, the rod 14 constituting the medium whereby 70 the result is effected in a positive manner.

By referring to Fig. 1 it will be seen that the journal 12 has a slot comprising three steps or notches 15, 15', 15'', within which a feather projection 16 is movable as controlled by the longitudinal movement of the rod 14 to which the feather 16 is attached or of which it may be an integral part as illustrated in Fig. 8. The rod 14 has also another feather 17 which is adapted to be 75 positioned in notches 18, 18', 18'' of a slot formed in the adjacent journal 11 of the other plate 10, the complete slots being substantially right and left hand as can be readily seen by a comparison thereof in Fig. 1, 80 in which the notches 15 and 18 are substantially in alinement, and therefore adapted to receive the feathers 16, 17, respectively, of the rod 14, (see Fig. 7), in which position the two plates are positively locked against 85 swinging movement relative to each other. When now the rod 14 is pulled downward to the position shown in Fig. 1 (by the handle end 14'), viz: so as to bring the feathers 16, 17 into the notches 15', 18', both plates 90 may be swung away from each other into the position shown in Figs. 3 and 4, where the fingers 10', 13' are still in engagement, and now permit the leaves to be turned over as usual for inspection without crowding, 95 and by virtue of the increased arc. It will be noted that the plates are here locked against further opening movement. However, when the rod 14 is pulled downward to bring the feathers 16, 17 into the notches 15'', 18'', the plates may be opened to the 100 limit as shown in Figs. 5 and 6, in which the ends of the fingers 10', 13' are spaced to permit ready insertion or removal of leaves therefrom. As in some instances, it 105 110

may become desirable to lock the plates in their wide-open position, the notches 15'', 18'' may have branches 15^a, 18^a just deep enough to permit the feathers 16, 17 to be 5 drawn thereinto, in which case both plates would be positively locked against movement in either direction, a condition which also exists when the feathers are in the necks connecting the notches 15', 15'', and 10 18', 18''.

From the foregoing it will be understood that my improved binder consists of the fewest number of parts possible and that it is adapted to perform its work in a very 15 satisfactory manner.

Many changes may be made in the particular construction and organization of the several elements of my improved device, without departing from the spirit of the 20 invention especially as to the shape of the locking slots, or the locking rod, and the fingers.

I claim:

1. A loose-leaf binder comprising a pair 25 of plates laterally movable toward and away from each other and having interlocking portions provided with opposed slots, fingers on said plates, and a longitudinally 30 slideable device in engagement with both of said plates and having feathers entering said slots, and for controlling their position relative to each other.

2. A loose-leaf binder comprising a pair 35 of adjacent plates having interlocking hinge- portions provided with opposed slots, fin-

gers on said plates, and a hinge-rod in longitudinal sliding engagement with said hinge-portions and having feathers in said slots, respectively, for controlling the angular position of said plates relatively to 40 each other.

3. The combination with a pair of adjacent finger-plates, each having a rolled-over hinge journal overlapping and in axial alignment with the other hinge-journal, said 45 journals being provided with longitudinal opposed slots, of a hinge rod longitudinally movable in said journals, and feathers on the rod and in said slots, respectively, for locking said plates against opening from a 50 predetermined position.

4. The combination with a pair of adjacent finger-plates, each having a rolled-over hinge journal overlapping and in axial alignment with the other hinge-journal, said 55 journals being provided with longitudinal opposed slots each composed of a series of connected notches angularly disposed around the axis of the journals, of a hinge-rod longitudinally movable in said journals, and 60 feathers on the rod and in said notches, respectively, for locking said plates against opening from a predetermined position.

In testimony whereof I affix my signature in presence of two witnesses.

WILLIAM C. LOUD.
